UNITED STATES PATENT OFFICE

OSCAR JUNGGREN, OF SCHENECTADY, NEW YORK, ASSIGNOR TO GENERAL ELECTRIC COMPANY, A CORPORATION OF NEW YORK

ELASTIC FLUID TURBINE

Application filed August 28, 1930. Serial No. 478,424.

This invention relates to multi-stage elastic fluid turbines, and more particularly to the construction of the inner or diaphragm carrying shells therefor.

Due to uneven expansion and contraction caused by the differences in temperature of the elastic fluid passing through an exhaust hood, stresses and strains are set up in the hood, and also in the inner shell. Due to the fact that the upper half of the inner shell is more flexible than the lower half, it may be formed as part of the exhaust hood, since, by reason of its flexibility and design, it will not be affected by the change in temperature of the fluid passing through the exhaust hood. The lower half of the inner shell, however, is much stiffer and more rigid than the upper half due to the fact that it supports the weight of the diaphragms and by reason of its difference in design, is not as flexible and therefore not as free to expand and contract as the upper half. Differences in temperature of the elastic fluid will therefore affect the respective portions of the shell unequally, resulting in uneven expansion and contraction of the shell, thereby causing undesirable strains and stresses, and tending to affect the centering of the diaphragms.

The object of my invention is to mount the inner shell, or part of it, so that it will be supported independently of the exhaust hood and will expand or contract freely.

For a consideration of what I believe to be novel and my invention, attention is directed to the following description and the claims appended thereto.

In the drawings,

Fig. 1 is a front elevation of the turbine with parts broken away disclosing the interior to show the arrangement of the shaft, buckets, diaphragms, inner shell and exhaust hood, as well as the guide for the lower half of the inner shell.

Fig. 2 is a section thru Fig. 1 on the line 2—2, parts being broken away to show the guides for the lower half of the inner shell.

Fig. 3 is a section on line 3—3 of Fig. 2, and

Fig. 4 is a section on line 4—4 of Fig. 1.

Referring to the drawings the shaft 1 carries the bucket wheels 3, to which are at-

tached the buckets 2, in the usual manner, the shaft being mounted for rotation in the bearings 4. Between the bucket wheels are the diaphragms 5 carrying the usual nozzles 6.

The diaphragms are mounted on the inner shell 7, which as shown in the drawings is divided horizontally at 8 into an upper half and a lower half. The shell is further divided centrally along a vertical axis into right and left hand portions as shown at 9. The exhaust hood 10 is divided similarly to the inner shell to provide ease in assembling.

As shown in Figs. 1 and 2, the upper portions of the inner shell are formed integral with the exhaust hood. In the present instance I have shown the upper portion of the inner shell as comprising inwardly projecting webs or walls 10a having portions 10b provided with recesses or grooves into which outer portions of the diaphragms project. With such an arrangement sidewise movement of the diaphragms relative to the outer shell is prevented. The walls 10a near the center of the turbine define a channel for conveying elastic fluid to the first stage or stages of the turbine. Furthermore, the inner walls 10a are comparatively long and thin and thus provide for flexibility of the portions defining the recesses. This flexibility is further increased by separating the inner, upper half shell into a plurality of portions, in the present instance shown as comprising an outer portion 10c and an inner portion 10d for each half of the double flow turbine. Portions 10c and 10d define clearances indicated at 10e.

From another aspect, I do not provide a separate inner, upper half shell in the customary manner but replace such shell by means integrally united with the outer, upper half shell for maintaining a definite relation between the diaphragms and the outer shell and for defining a fluid supply channel to the first stage or stages of the turbine. This is an important feature of my invention as it provides for a light construction of the upper turbine parts. The lower portions 11 of the shell are held together by bolts 12, and formed separate from the hood, but supported by the lower half thereof, being provided with shoulders 100

or ledges 13 which serve as supports for the flanges 14 of the inner shell, see Fig. 2.

Guiding means, such as are shown in detail in Figs. 3 and 4, are provided to prevent side and end movement of the inner shell, while permitting movement of the flanges 14 relative to the shoulders 13. Sidewise movement of the shell is prevented by the webs 15 and 16 formed on the respective portions of the lower half of the exhaust hood, which coact with cooperating lugs, 17 and 18, formed on the corresponding portions of the lower half of the inner shell. There is also provided on the exhaust hood a web 19, extending at right angles to the webs 15 and 16, which coacts with pairs of lugs 20, 20, and 21, 21, on the respective portions of the lower half of the inner shell, to prevent end movement of the shell. From the exhaust hood the fluid passes through the opening 22 to the usual condenser (not shown), the fluid being admitted through the usual conduits 23, 23. Arrows in Fig. 2 indicate the direction of flow of fluid through the turbine.

By the above arrangement and construction of parts, it will be apparent, that the inner shell is not constrained to follow or participate in the distortions of the exhaust hood, due to changes therein, caused by the differences in temperature in the fluid passing therethrough, and that the lower half of the inner shell at the points where it is supported on the exhaust hood, is free to move of its own accord relative to the exhaust hood and that the guiding means 15, 16, 17, 18, 19, 20 and 21, while permitting such movement of the lower half of the inner shell, will hold the diaphragms carried thereby in central position regardless of the changes in diameter of the inner shell.

By my invention I provide a reliable construction for turbines capable of being built at relatively low cost. The weight of the inner shell is considerably decreased by omitting a separate upper half shell and replacing same by means united with the upper half of the outer shell or casing. This arrangement is particularly advantageous where the outer shell or casing defines an exhaust hood for the turbine with lower portions of the hood connected to a condenser. In constructions of this kind it is customary to have the weight of the condenser carried by the lower part of the exhaust hood. This necessitates that the upper turbine parts be made as light as possible. The light and simplified construction of the upper portions of the exhaust hood and the inner shell also permits manufacturing of the turbine at low cost.

In accordance with the provisions of the patent statutes, I have described the principle of operation of my invention, together with the apparatus which I now consider to represent the best embodiment thereof, but I

desire to have it understood that the apparatus shown is only illustrative and that the invention may be carried out by other means.

What I claim as new and desire to obtain by Letters Patent of the United States is:

1. In an elastic fluid turbine, a rotor comprising a shaft and bucket wheels fastened to the shaft, diaphragms interposed between the bucket wheels, a lower inner half shell for supporting the diaphragms, flanges provided on the lower inner half shell, a lower outer half shell supporting the lower inner half shell, and means provided between the lower shells to allow relative movement between them, a single upper shell fastened to the lower outer half shell and having flanges which engage those of the inner lower half shell, said upper half shell including inwardly projecting webs having end portions provided with recesses into which outer portions of the diaphragms project.

2. In an elastic fluid double flow turbine, a rotor including a plurality of diaphragms, an exhaust hood having an upper portion provided with inlet conduits for elastic fluid, an inner half shell, means provided between a lower portion of the exhaust hood and the inner half shell for permitting relative expansion between them, webs integrally united with upper portions of the exhaust hood for defining an annular channel through which elastic fluid is supplied to the first stages of the turbine, inner portions of the webs having recesses into which outer portions of the diaphragms project.

In witness whereof, I have hereunto set my hand this 27th day of August, 1930.

OSCAR JUNGGREN.
